COMBINATION SOUND RECORDER AND
REPRODUCER

Albert W. De Sart, Sr., Los Angeles, Calif., assignor to United Acoustigraph Corporation, Los Angeles, Calif., a corporation of Nevada

Application November 17, 1941, Serial No. 419,361

19 Claims. (Cl. 179—100.4)

This invention relates to apparatus for recording and reproducing sound. More particularly, the apparatus contemplates the use of a stylus that forms a record groove, for recording, or that cooperates with a previously formed groove for reproduction.

The record in such apparatus is usually formed on a plastic record carrying member, which may be in the form of a disc or cylinder or a flexible loop, guided over appropriate rollers. In the recording operation, the stylus is urged against the record surface while the record is moved linearly; and at the same time, the stylus is moved in a direction transverse to the motion of the record, so as to form a helical-like groove on the record blank. The stylus is vibrated in accordance with the sound waves to be recorded. Usually this is effected by an electric translating device, which converts electrical impulses corresponding to the sound waves impressed on a microphone, into mechanical vibrations. Such translating devices are now well known, and require no explanation.

In the reproduction operation, the stylus is caused to follow the previously formed record groove, and the stylus is vibrated in accordance with the undulations formed in the sides or the bottom of the record groove. The vibrations affect the translating device, which converts them into electrical impulses, capable of being amplified and to operate a generator of sound waves, such as a loud speaker of a telephone receiver. This general system for the reproduction of sound is also well understood in general and further detailed description is not necessary.

In order to make it possible to utilize the same apparatus for reproduction as well as for recording, certain features of operation must be considered. For example, in the process of recording, the stylus is urged strongly against the record blank, in order to provide a sufficient force for forming the record by a displacement of the material of the blank. Such a displacement may be either a definite cutting of a groove, or an embossing in which the groove is formed by pressure alone. However, for reproduction purposes, the pressure upon the stylus is much less, so as to enable it to follow the undulations without undue friction or wear.

It is one of the objects of this invention to make it possible to adjust the stylus head in a simple manner so as to select the pressure acting on the stylus for optionally performing either the operation of recording or reproducing.

In a recording operation, the stylus is moved

as by a lead screw, in a path transversely of the direction of motion of the record blank. The stylus for this operation must be so supported as to provide a rigid support for the stylus, thereby causing the recording vibrations of the stylus to be freely effective. In reproduction, however, the stylus support is so arranged as to have "lateral compliance," so that the stylus is permitted to accommodate itself readily to any slight vagaries of the groove. It is another object of this invention to provide a simple control for optionally permitting or preventing lateral compliance.

It is still another object of this invention to provide a novel and simple control device by the aid of which the stylus head may be optionally rendered inactive, or conditioned for either recording or reproduction.

It is usual to provide an amplifier system arranged to amplify the electrical impulses that are used to operate the stylus for recording, or that are produced by the stylus head during reproduction. It is another object of this invention to make it possible automatically to cause the amplifier system to be properly connected in the stylus mechanism when the mechanism is conditioned for either a recording or a reproducing operation.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

40 In the drawings:

Figure 1 is a view, mainly in longitudinal section, of a phonograph apparatus incorporating the invention;

Fig. 2 is a front elevation as seen in the direction of arrow of Fig. 1;

Fig. 3 is a fragmentary elevational view taken along the plane 3—3 of Fig. 1;

Figs. 4, 5, 6, 7, 8, 9, 10 and 11 are fragmentary sectional views taken along correspondingly numbered planes of Fig. 1;

Fig. 12 is a horizontal sectional view taken along the plane 12—12 of Fig. 1;

Fig. 13 is a fragmentary pictorial view of one of the elements utilized in connection with the apparatus illustrated in Fig. 1.

Fig. 14 is a view similar to Fig. 1 illustrating the stylus head out of operative relation with the record carrying member;

Fig. 15 is similar to Fig. 1, illustrating the position of the stylus head when utilized for reproduction purposes; and

Fig. 16 is a wiring diagram of a system in which the stylus head is incorporated for optionally providing a recording or reproducing operation.

In Figs. 1, 2, 6, 14 and 15, a member 1 is illustrated which is capable of carrying a record groove. While this record groove carrying member may take any conventional form it is illustrated in this instance as being made from thin flexible material as of cellulose acetate or the like, and capable of passing over an anvil roller 2. The roller 2 may be a driving roller driven from any appropriate source of power so as to move the loop past a stylus 3. The apparatus 5 is a translating device capable of being utilized for either recording or reproduction operations. In the recording position of Fig. 1, the translating device 5 is arranged to convert electrical impulses into vibratory impulses of the stylus 3. These vibratory impulses when the device is in the position of Fig. 1, cause a groove record to be formed on the record carrying member 1 in a well understood manner.

In the reproducing position illustrated in Fig. 15, the translating device is so arranged that it converts mechanical vibrations of the stylus 3 into electrical impulses. In the inactive position illustrated in Fig. 14 the stylus member 3 is out of contact with the record carrier 1 and the stylus head is inactive.

Appropriate interlocking mechanism is provided for making it possible to place the stylus head into the appropriate positions required optionally for recording, reproducing or for rendering the apparatus inactive as illustrated in Fig. 14.

Fig. 16 illustrated in diagrammatic fashion how the switching may be effected for rendering the translating device 5 effective for converting electrical impulses into mechanical vibrations or vice versa.

In this figure the stylus head 6 is diagrammatically illustrated as being capable of connection either to the input side or the output side of an amplifier system 7, as by the aid of the switching devices 8 and 9. With the switches in the position illustrated, sound impulses are first of all converted into electrical impulses as by a microphone circuit, including microphone 10. These electrical impulses are caused to affect the input side of the amplifier 8 as by the aid of the switch mechanism 11. The output side of the amplifier is connected by the aid of the switch mechanism 9 to the stylus head 6. In this position therefore the apparatus is in recording condition.

For reproduction purposes the switch 8 is closed and the switch 9 is opened. Furthermore, switch 11 is open and switch mechanism 12 is closed. In this position mechanical vibrations imparted to the stylus 3 are passed to the amplifier input through the closed switch 8; the amplifier output is connected by way of closed switch 12 to the sound reproducer or loud speaker 13. The reproducer or loud speaker 13 is shown merely as one form of apparatus that is capable of utilizing the amplified electrical impulses.

It is possible by the aid of the apparatus as hereinafter explained to cause both switches 8 and 9 to be opened, rendering the stylus head 6 ineffective, while maintaining switches 11 and 12 closed. In this position the electrical im-

pulses produced by sound vibrations in the microphone circuit are passed to the input side of the amplifier 7. The output side directly affects the loud speaker mechanism 13 through the closed switch 12. In this position any speech or sound affecting the microphone 10 can be listened to by the aid of the loud speaker 13.

The stylus 3 and its associated mechanism are so arranged to be advanced in a direction transversely of the recording loop 1. This is effected by the aid of a lead screw 14 (Figs. 1, 3, 8, 14 and 15). The axis of this screw is shown as parallel to the axis of the roller 2, and it may be driven by the same source or motion as the roller 2. The lead screw 14 cooperates with a mutilated nut 15 supported upon a flexible or spring arm 16. This spring arm in turn as illustrated most clearly in Figs. 3 and 8, is fastened to an upright arm 17. This arm 17 is shown as formed integrally with a carriage 18 appropriately formed as a casting. This carriage 18 has another arm 19 parallel with arm 17 and forming a fork-like structure. The carriage 18 also has a pair of downwardly extended arms 20 and 21. The carriage 18 is guided for movement in a direction parallel to the axis of lead screw 14 as by the aid of the stationary guide bar 22 passing through the upper ends of the arms 17 and 18; as well as by a similar stationary guide bar 23 (Fig. 1) engaged in corresponding slots in the arms 20 and 21. The arms 20 and 21 are both provided with bosses 24 for supporting a restraining strip 25 for maintaining the carriage 18 in proper operative relation to the guide bar 23.

The translating device 5 with the stylus 3 is supported upon the frame or carriage 18 and accordingly they are advanced by the coaction of the lead screw 14 and the mutilated nut 15. For this purpose the right hand end of the device 5 is shown as fastened to the upright arm 26 of a supporting member 27 (Figs. 1, 12, 14 and 15). As shown most clearly in Figs. 1, 8 and 15, this member 27 is shown as pivotally mounted upon a support 28. This support 28 has a pair of parallel ears 29 through which pass the conical pivot screws 30. The conical points of these screws engage corresponding conical recesses on opposite sides of the supporting member 27. The translating device 5 and its associated stylus 3 is urged by gravity in a counterclockwise direction about the axis of the pivot screws 30, and the stylus 3 is accordingly in operative contact with the record carrying member 1.

This force of gravity is sufficient for creating the necessary light pressure upon the stylus 3 when the apparatus is used for reproduction. The manner in which this pressure may be increased for the purpose of recording will be hereinafter described.

During the process of reproduction it is also necessary to permit the stylus 3 to have some lateral compliance with relation to the record; that is, it should be free to follow the vagaries of the groove without restraint. For this purpose the support 28 is shown as being pivoted upon an axis 31. This is accomplished by the aid of a downwardly extending shank 32 which is journaled in the carriage 18. The support 28 is restrained from movement in a direction along the axis 31 by the aid of the shoulder formed by the boss 33 (Fig. 8), and the washer 34 and nut 35 mounted upon the lower threaded end of the shank 32.

The translating device 5 with its associated parts is shown as protected by a covering or hous-

ing 36. This hosing as shown most clearly in Figs. 1, 8 and 12, is in the form of a sheet metal structure having depending sides and a depending front portion. This front portion is provided with a slot 37 (Fig. 1) through which the thumb screw 4 may pass. The housing 36 is held rigidly in place with relation to the carriage 18 as by the provision of the rearwardly extending portions 38 and 39 (Figs. 8 and 12). These portions contact respectively the inner faces of the upright arms 17 and 19 and may be fastened thereto as by the aid of screws such as 40 (Figs. 1 and 12).

Provisions are made as stated hereinbefore to increase the pressure exerted by the stylus 3 for the purpose of recording. By the aid of the present mechanism not only is the pressure increased, but at the same time the lateral compliance of the device 5 is rendered ineffective. In other words, the support 28 is restrained against angular movement with respect to its axis 31.

For accomplishing this purpose a weight member 41 is utilized (Figs. 1 and 6). This weight member has an upper portion extending across the translating device 5 and has two weighted sides 42 and 43 embracing the device 5. As shown most clearly in Figs. 1 and 12 this weight 41 is provided with rearwardly extending parallel arms 44. The extremities of these arms are formed with apertures through which a pivot rod 45 passes. This pivot rod is supported in appropriate bosses formed in the right hand end of the extensions 38 and 39 of the housing 36.

As shown most clearly in Fig. 6, the lower surface of the weight 41 is provided with a tapered recess 47 adapted to receive the tapered projection 48 provided on top of the device 5. The aperture 47 and the projection 48 have a substantial length in a direction longitudinal of the weight as illustrated most clearly in Figs. 1 and 15. Accordingly when the weighted member 41 is in the engaged position of Fig. 1, the engagement of projection 47 in the recess 48 restrains lateral movement of the device 5 with respect to the carriage 18. Accordingly lateral compliance is eliminated.

When it is desired to place the apparatus in condition for reproduction as illustrated in Fig. 15, the weight member 41 is lifted free of the device 5. The mechanism whereby this is accomplished will now be described.

In order to form a supplemental guide for the engaging and disengaging movement of the weight member 41, this weight member 41 is provided with a pair of upright guiding bars 49, shown most clearly in Fig. 6. These guiding bars pass through appropriate guiding apertures in the top of the housing 36. They are connected near their upper ends by cross bar 50. In order to lift the weight 41 into the position of Fig. 15 as desired, use is made of a cam 51 mounted on a shaft 52. This shaft is journaled adjacent its right hand end in a standard 53 (Figs. 1, 14 and 15). The cam 51 is shown as provided with an integral hub 54 that is journaled in another standard 55 adjacent the left hand end of the apparatus. Axial movement of the shaft 52 is prevented by the aid of a collar 56 adjacent the right hand surface of the standard 53, and by the aid of a collar 57 adjacent the left hand surface of standard 55. Collar 57 may be provided with a handle 58 (Figs. 1, 2, 3 and 14). By the aid of this handle the angular position of the shaft 52 may be adjusted so as to move the cam 51 to the inactive position of Fig. 6. In this position the

weight 41 is effective. When the handle 58 is moved through 180° in a counterclockwise direction as illustrated in Fig. 2, the cam 51 acts against bar 50 and is effective to hold the weight 41 out of operative position (Fig. 15).

Provisions are made in connection with standard 55 to maintain the shaft 52 in any of a number of angular positions. The manner in which this is accomplished is shown most clearly in Figs. 1 and 7.

The hub 54 is provided with a series of arcuate depressions 59, 60 and 61 having a space of 90°. Adapted to cooperate with any one of these depressions is a ball restraint 62 movable in a vertical aperture 63. The ball restraint 62 is urged as by a compression spring 64 downwardly into engaging position. The compression spring is held in place by headless screw 65 engaging the upper threaded portion of the bore 63. In the position of Figs. 1 and 6 with the weight in operative position, the ball 62 is in engagement with the recess 60. When the handle 58 is rotated through 180° in a counterclockwise direction to the position of Fig. 2, the ball 62 cooperates with recess 59. In this way the shaft 52 may be maintained resiliently in either of its two positions. The intermediate recess 60 is utilized in a manner to be hereinafter described, when the stylus 3 to be lifted clear of the record member 1 (Fig. 14).

In order to make it possible to lift the stylus 3 and its associated translating device 5 out of operative relation with respect to the record member, as shown in Fig. 14, a mechanism is utilized that is illustrated most clearly in Figs. 1, 5 and 14. For this purpose the swinging support 27 is provided at its right hand end with an upright member 66. This upright member as shown most clearly in Fig. 5 is provided with an upward tapering point 67. When this point is urged downwardly or in a clockwise direction with respect to the axis of the support 27, the device 5 and the stylus 3 are caused to move upwardly to the position of Fig. 14. For accomplishing this movement use is made of a bar 68. This bar 68 is provided at its right hand free end with a tapered recess 69 adapted to cooperate with the point 67. In the position of Figs. 1 and 15, this bar 68 is out of contact with the point 67.

The bar 68 is pivotally mounted by the aid of the ears 70 (Fig. 3). This pivotal mounting is adjacent the left hand end of the bar 68. Normally the bar 68 is urged upwardly so as to clear the point 67 as by the aid of a U-shaped leaf spring 71 interposed between the lower side of the bar 68 and the upper surface of the housing 36.

When it is desired to depress the bar 68 to the position of Fig. 14, the shaft 52 is rotated until the ball restraint 62 cooperates with the intermediate recess 60. This 90° rotation in a counterclockwise direction from that shown in Fig. 2 causes corresponding rotation of a cam 72 mounted on the right hand end of shaft 22. This cam 72 is shown to best advantage in Figs. 8 and 13. In the active position, the raised portion of one side of the cam 72 depresses the bar 68, and the stylus head mechanism including the translating device 5 and stylus 3 are tilted upwardly to the position of Fig. 14. It is noted that when either a recording or reproducing position is obtained by rotation of the shaft 22 through an angle of 90° in either direction from the inactive position of Fig. 14, this cam 72 is rendered inactive; therefore for either of these two ex-

trete positions (illustrated in Figs. 1 and 15) the stylus 3 is maintained in operative relation with the record carrying member 1.

The cam 72 is also provided with a projection 73 forming a crown cam surface and extending in a direction parallel to the axis of shaft 72. This cam projection 73 causes disengagement of the mutilated nut 15 from the lead screw 14. For this purpose the resilient arm 16 which supports the nut 15 is provided with a depending portion 74 in the path of the cam portion 73. When the shaft 22 is rotated in such a direction as to lift the stylus 3 from a record carrying member 1, this cam 73 engages behind the portion 74 and flexes the arm 16 to the position indicated in Fig. 14. In this position therefore the stylus head is disengaged from the driving mechanism.

It may also be convenient to operate the switch devices 11, 8, 9 and 12 of Fig. 16 in accordance with the movement of the shaft 22 to the corresponding positions.

The switching means in this case is shown as comprising a series of eight pairs of spring fingers supported upon one wall of a casing 76, by the aid of a series of insulation strips. This casing 76 is made from sheet metal. As shown most clearly in Figs. 3 and 4, it is provided with the side flanges 77 by the aid of which it may be attached to the top of the housing 36.

The insulation material supporting the contact fingers (Fig. 4) comprise the insulation bars 75, 75' and 78. Since the pairs of spring fingers are quite similar in structure, the spring fingers adjacent the left hand portion of the casing 76 only need be described in detail. These are shown in Fig. 4. Thus the spring fingers 79 and 79' are positioned one over the other, and spaced apart by the aid of the insulation bar 75'. In their free position the contact points 80 and 81 carried by the fingers are disengaged. The next adjacent pair of spring flowers 82 are entirely similar to the spring fingers 79 and 79'. These two pairs of spring fingers 79-79', and 82 correspond to the switching means 11 of Fig. 16. They are controlled by a common cam 83 mounted on shaft 52. This cam 83 is of such configuration that the switching means 11 remains closed for either the recording position or for the position corresponding to inactivity of the stylus 3. However, for reproduction purposes, it is apparent that a cam rotation of 180° from the position of Fig. 4 will permit the spring fingers 79 and 79' and the corresponding pair of spring fingers 82 to separate, and the circuit is broken at the switching means 11. Accordingly the microphone circuit is active at all times except when reproduction is desired.

In the recording position illustrated in Fig. 16, the switch mechanism 9 corresponding to the two pairs of spring fingers 84 of Fig. 1 are maintained in engagement. One pair of these spring fingers is illustrated in greater detail in Fig. 11. Here the cam 85 cooperating with these spring fingers is so arranged that the spring fingers are out of contact except when the shaft 52 is rotated to the reproducing position.

The pairs of spring fingers 88 correspond to the switch mechanism 12 of Fig. 16. They are shown in greater detail in Fig. 10. These spring fingers control the connection of the loud speaker or sound reproducer 13 to the amplifier output. These spring fingers make contact when the apparatus is placed in reproducing position or when the stylus 3 is lifted out of engagement with the

flexible record carrying member 1. This is accomplished by the aid of the cam 89 of the configuration shown in Fig. 10, and mounted on shaft 22.

5 The various connections to the spring fingers are accomplished by the aid of a cable 90 (Figs. 1, 4 and 8) held as by the aid of a clip 91 mounted on the upright arm 17. Two leads from this cable extend as shown in Fig. 1 to the translating device 5. Other leads connect to the corresponding appropriately formed ears provided on the upper ends of the spring fingers.

From the foregoing it is seen that the adjustment of the apparatus for recording, reproducing or listening in is effectively accomplished by appropriate annular rotation of shaft 52 and the corresponding mechanical interlocks that cooperate with the translating device 5 and the switching mechanisms.

What is claimed is:

1. In a phonograph apparatus, a stylus head, means for mounting said head in operative relation to a member capable of carrying a record groove, and permitting relative free movement in a direction lateral of the record groove, and a movable weight structure adapted optionally to be free of the head, so that the head may operate as a reproducer, or to cooperate with the head to increase the stylus pressure as well as to restrain the head from lateral motion with respect to the mounting means, so that the head may operate as a recorder.

2. In a phonograph apparatus, a stylus head, a pivot structure for the head to permit motion of the head in a direction toward and from a member capable of carrying a record groove, as well as for permitting angular movement of the head in a direction lateral of the record groove, a movable weight member adapted optionally to be free of the head, so that the head may operate as a reproducer, or to cooperate with the head to increase the stylus pressure, and means for guiding the movement of the weight member in such manner that when the weight member is effective to increase the pressure, said guiding means cooperates to restrain lateral movement of the head, so that the head may operate as a recorder.

3. In a phonograph apparatus, a stylus head, a pivot structure for the head to permit motion of the head in a direction toward and from a member capable of carrying a record groove, as well as for permitting angular movement of the head in a direction lateral of the record groove, a weight member cooperating with said head, said weight member and head having a detachable connection formed by a projection and a groove, and means for movably mounting said weight to engage or disengage said connection, said connection when established serving also to restrain lateral motion of said head.

4. In a phonograph apparatus, a stylus head, a lead screw for moving the head, a mutilated nut engaging the screw, a leaf spring support for the nut, a bearing support for the head, and a cam device for angularly moving the head into inactive position, as well as for urging the leaf spring support to move the nut out of engagement with the screw.

5. In a phonograph apparatus, a stylus head movable into active or inactive position, a device for increasing the pressure upon the stylus head, cam means for controlling position of the stylus head, cam means for controlling the pressure increasing device, and a common means for operating both of said cam means.

6. In a phonograph apparatus, a stylus head movable into active or inactive position, disconnectible means for traversing the head in relation to a member capable of carrying a record groove, cam means for controlling the position of the stylus head, cam means for disconnecting the traversing means, and a common angularly adjustable means upon which both said cam means are mounted.

7. In a phonograph apparatus, a stylus head movable into active or inactive position, disconnectible means for traversing the head in relation to a member capable of carrying a record groove, means for optionally increasing the pressure upon the head, cam means for controlling the position of the stylus head, cam means for disconnecting the traversing means, cam means for controlling the pressure increasing means, and a common angularly adjustable means upon which all said cam means are mounted.

8. In a phonograph apparatus, a stylus head movable into active or inactive position, disconnectible means for traversing the head in relation to a member capable of carrying a record groove, means for optionally increasing the pressure upon the head, means cooperating with the head and the pressure increasing means for restraining the stylus head against free lateral movement when the pressure increasing means is active, cam means for controlling the position of the stylus head, cam means for disconnecting the traversing means, cam means for controlling the pressure increasing means, and a common angularly adjustable means upon which all said cam means are mounted.

9. In a phonograph apparatus, a stylus head movable into active or inactive position, a device for increasing the pressure upon the stylus head, cam means for controlling position of the stylus head, cam means for controlling the pressure increasing device, a common means for operating both of said cam means, and amplifier control switching means also operated by said common means for establishing appropriate connections corresponding to the angular position of said plurality of cam means.

10. In a phonograph apparatus, a stylus head movable into active or inactive position, disconnectible means for traversing the head in relation to a member capable of carrying a record groove, cam means for controlling the position of the stylus head, cam means for disconnecting the traversing means, a common angularly adjustable means upon which both said cam means are mounted, and amplifier control switching means also operated by said common means for establishing appropriate connections corresponding to the angular position of said plurality of cam means.

11. In a phonograph apparatus, a stylus head movable into active or inactive position, disconnectible means for traversing the head in relation to a member capable of carrying a record groove, means for optionally increasing the pressure upon the head, cam means for controlling the position of the stylus head, cam means for disconnecting the traversing means, cam means for controlling the pressure increasing means, a common angularly adjustable means upon which all said cam means are mounted, and amplifier control switching means also operated by said common means for establishing appropriate connections corresponding to the angular position of said plurality of cam means.

12. In a phonograph apparatus, a stylus head 75

movable into active or inactive position, disconnectible means for traversing the head in relation to a member capable of carrying a record groove, means for optionally increasing the pressure upon the head, means cooperating with the head and the pressure increasing means for restraining the stylus head against free lateral movement when the pressure increasing means is active, cam means for disconnecting the traversing means, cam means for controlling the pressure increasing means, a common angularly adjustable means upon which all said cam means are mounted, and amplifier control switching means also operated by said common means for establishing appropriate connections corresponding to the angular position of said plurality of cam means.

13. In a phonograph apparatus, a stylus head, disconnectible means for traversing said head in relation to a member capable of carrying a record groove, means for optionally conditioning the head either for recording or reproduction, said conditioning means including a device for restraining lateral motion of the head, means for disconnecting the traversing means, and a common mechanism for controlling the disconnectible means and the conditioning means, comprising an angularly adjustable shaft, having definite angular positions corresponding to the control functions.

14. In a phonograph apparatus, a stylus head, disconnectible means for traversing said head in relation to a member capable of carrying a record groove, means for optionally conditioning the head either for recording or reproduction, said conditioning means including a device for restraining lateral motion of the head, means for disconnecting the traversing means, and a common mechanism for controlling the disconnectible means and the conditioning means, comprising an angularly adjustable shaft, having three angular positions, corresponding respectively to a recording position, a reproducing position, and an inactive position.

15. In a phonograph apparatus, a stylus head movable into active or inactive position, a device for increasing the pressure upon the stylus head, means for controlling the position of the stylus head, means for controlling the pressure increasing device, and a common means for operating both of said means.

16. In a phonograph apparatus, a stylus head capable of operating optionally as a recording head or a reproducing head, means for traversing the head with respect to a record, pivotal means adapted to provide lateral compliance for the head, a pivoted weight adapted to engage the head to restrain the head about the pivotal means and to apply a force of gravity for recording purposes, and means for lifting the weight out of engagement with the head.

17. In a phonograph apparatus, a stylus head capable of operating optionally as a recording head or a reproducing head, means for traversing the head with respect to a record, pivotal means adapted to provide lateral compliance for the head, a pivoted weight adapted to engage the head to restrain the head about the pivotal means and to apply a force of gravity for recording purposes, an extension connected to the weight, and a pivoted arm adapted to engage said extension to move the weight out of engagement with the head.

18. In a phonograph apparatus, a stylus head capable of operating optionally as a recording

head or a reproducing head, a carriage for the head, a lead screw for traversing the head, a multilated nut adapted to be placed into and out of engagement with the screw and carried by the carriage, a weight mounted on the carriage and movable optionally to engage the head for recording purposes, and to be disengaged from the head for reproducing purposes, an angularly adjustable shaft mounted on the carriage and having an axis transverse to the screw, means operated by the shaft for causing the nut to move into and out of engagement with the screw, and means operated by the shaft for lifting the weight out of engagement with the head.

19. In a phonograph apparatus, a stylus head capable of operating optionally as a recording head or a reproducing head, a carriage for the

head, a lead screw for traversing the head, a mutilated nut adapted to be placed into and out of engagement with the screw and carried by the carriage, a weight mounted on the carriage and movable optionally to engage the head for recording purposes, and to be disengaged from the head for reproducing purposes, an angularly adjustable shaft mounted on the carriage and having an axis transverse to the screw, means operated by the shaft for causing the nut to move into and out of engagement with the screw, and means operated by the shaft for lifting the weight out of engagement with the head, the angular position of the shaft determining the operation of said nut and of said weight.

ALBERT W. DE SART, SR.
